US0D1077793S

(12) **United States Design Patent** (10) **Patent No.:** **US D1,077,793 S**
(45) **Date of Patent:** **** Jun. 3, 2025**

(54) **LAPTOP COMPUTER**

(71) Applicant: **Getac Technology Corporation**, New
Taipei (TW)

(72) Inventors: **Chun-Hsing Li**, Taipei (TW);
Shi-Liang Zhong, Taipei (TW)

(73) Assignee: **Getac Technology Corporation**, New
Taipei (TW)

(**) Term: **15 Years**

(21) Appl. No.: **29/925,358**

(22) Filed: **Jan. 24, 2024**

(51) LOC (15) Cl. **14-02**

(52) U.S. Cl.

USPC **D14/315**

(58) **Field of Classification Search**

(57) **CLAIM**

The ornamental design for a laptop computer, as shown and
described.

DESCRIPTION

FIG. 1 is a bottom, front, and left side perspective view of
a laptop computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the laptop computer that
form no part of the claimed design.

1 Claim, 7 Drawing Sheets
